UNITED STATES PATENT OFFICE.

LOUIS A. SUEKOFF, OF CHICAGO, ILLINOIS.

SPRING STRUCTURE FOR USE IN UPHOLSTERING.

1,205,406.

Specification of Letters Patent. Patented Nov. 21, 1916.

Application filed June 1, 1915. Serial No. 31,366.

To all whom it may concern:

Be it known that I, LOUIS A. SUEKOFF, a citizen of the United States, residing at Chicago, in the county of Cook and State of Illinois, have invented certain new and useful Improvements in Spring Structures for Use in Upholstering, of which the following is a specification.

My invention relates to improvements in spring structures for use in upholstering.

One of the objects of my invention is to provide a spring structure, complete within itself, adapted to be subsequently incorporated within upholstered mattresses, cushions, or the like.

Another and more specific object of my invention is to generally improve, simplify and cheapen the construction of such devices.

Other and further objects of my invention will become readily apparent to persons skilled in the art, from a consideration of the following description when taken in conjunction with the drawings, wherein:—

Figure 1 is a plan view of a completed mattress structure showing parts broken away to expose the several features thereof. Fig. 2 is a section taken on line 2—2 of Fig. 1. Fig. 3 is a section taken on line 3—3 of Fig. 1.

In all the views the same reference characters are employed to indicate similar parts.

One of the prime objects I have in view is the provision of a spring structure that is a complete entity within itself, independently of the upholstery, such as hair, felt, batting, or the like, and the covering thereof that may be subsequently applied to the spring structure, as when making mattresses, cushions or upholstering furniture.

Spring structures, of a class to which my invention relates, when made separately from and independently of the subsequently applied upholstery material may be constructed by a class of mechanics especially well skilled in that particular branch of the art and when completed may be furnished to others who are better skilled in the subsequent application of the upholstering materials to the spring structure, thus confining to the artisans the work which by prior training they are best adapted to perform, thereby to cheapen the construction efficiency of the completed article and the convenience of manufacture.

While I have herein shown my spring structure as it will appear when incorporated in a mattress, it is to be understood that the spring structure of itself is separate and independent of the subsequently to be applied material necessary for the construction of a mattress. And while my invention is equally applicable to other structures than mattresses, as for instance, cushions or the like, I have shown it herein in association with a mattress as one means for clearly disclosing the invention and its use.

In carrying my invention into effect I provide a top and bottom sheet, 5 and 6, respectively, of burlap or other suitable fabric, of suitable width and length for the structure to be made, and sew the longitudinal edges together as at 7, and at suitable intervals, I attach the two sheets together, as at 8, as by means of a tufting stitch, button or the like. I prefer to place these stitched portions at uniformly spaced apart intervals in longitudinal rows and after one row has been thus stitched I prefer to insert the springs 9—9 between the fabric sheets 5 and 6, as clearly shown in Figs. 2 and 3. The extension of the springs 9—9 has the effect to separate the covers or sheets 5 and 6 and to deform the intervening portion into funnel shaped pockets 10, with their apices connected together, thereby causing the fabric to be drawn down between adjacent springs, complete pockets being formed in the space between every four angularly disposed springs thereby placing at least two layers of fabric between adjacent spring surfaces. The distance of separation between the stitched together parts 8—8 will determine the thickness of the spring structure and to some extent the width of the conical pockets 10—10. After the springs have been inserted behind the first row of stitching 8—8, a second row of stitching 8—8 is made, in front of the first row, and a second series or row of springs is placed behind the second row of stitching. This is a convenient way of making the structure, although the entire stitching together at intervals of the upper and lower surfaces of the spring structure, or sheets 5 and 6, may be completed and the springs subsequently inserted by being collapsed with a proper pair of tongs or other instruments, and pushed into their proper positions.

After the springs have been placed be-

tween the sheets 5 and 6, in the manner heretofore described, I then prefer to pass cords or tapes, 11 longitudinally across the top and bottom ends of the springs, and as they 5 pass from one spring to the adjacent spring to pass it through the fabric, as at 12, and under the wire of one spring, as at 13, thence through the doubled fabric or inwardly projecting node 14, and under the wire 15, of 10 the adjacent spring, and then up through the fabric again as at 16, and secured thereto, as at 17, to a marginal spring, or in the case of an intermediate spring passing it across the upper surface of the said spring 15 and through the fabric and under the opposite side of the terminal coil thereof, as heretofore described. I then pass cords, or tapes 18—18, in a similar manner, transversely of the cords or tapes 11—11 and secure them as 20 at 19, in the same way, having passed them through the fabric and under the terminal rings of adjoining springs as in the first instance. The tapes or cords 11—11 and 18—18 serve as an additional means for 25 holding the springs in their relative positions.

In applying hair, felt or cotton, as in making a mattress 20, the conical pockets 10 are preferably to be filled with such material and the layers 21 and 22, are to be applied between the spring structure and the final coverings 23 and 24 of the mattress. The subsequent application of this upholstering material, to my spring structure, 35 however, is entirely independent of said structure and may be applied thereto and removed therefrom without affecting the said spring structure.

A spring structure when made in accordance with my invention is very resilient and yielding, is noiseless, as there is no contact 40 of any two parts of moving metal constituting the springs or other portions of the de-

vice, and will remain of uniform thickness, owing to the connected adjacent conical 45 pockets 10—10 serving as means for preventing unequal expansion of the springs, but permitting their contraction or compression without imposing any undue resistance thereto. 50

While I have herein shown a single embodiment of my invention for the purpose of clear disclosure it is evident that changes may be made in the formation and relation of the parts within the scope of the ap- 55 pended claim.

Having described my invention, what I claim is:—

A spring structure comprising a top and bottom sheet of fabric joined at their edges 60 to form a spring inclosing envelop, a plurality of coil springs arranged in parallel rows within the envelop with their ends abutting against the top and bottom sheets, said sheets being fastened together at spaced 65 apart intervals to provide inwardly tapering pockets between each four adjacent springs, the fabric being doubled in between adjacent spring ends to stretch the fabric tight across the spring ends and form nodes 70 therebetween extending below the spring ends, and cords, crossing the major portions of the spring ends outside the fabric at right angles and passing through the fabric to the inner side thereof near the spring coils 75 and through doubled-in folds of fabric at points inside the plane of the end coils to secure the spring ends to the fabric at the points of cord penetration.

In testimony whereof I hereunto set my 30 hand in the presence of two subscribing witnesses.

LOUIS A. SUEKOFF.

In the presence of—

FORÉE BAIN,
MARY F. ALLEN.
